UNITED STATES PATENT OFFICE.

DOROTHY McHOLLAND, OF MINNEAPOLIS, MINNESOTA.

UNDERGARMENT.

Application filed February 25, 1921. Serial No. 447,796.

To all whom it may concern:

Be it known that I, DOROTHY McHOLLAND, a citizen of the United States, residing at Minneapolis, in the county of Hennepin and State of Minnesota, have invented certain new and useful Improvements in an Undergarment, of which the following is a specification.

This invention relates to women's apparel 10 and more particularly to undergarments for women.

The object of the invention is to provide a three-in-one garment comprising a camisole and petticoat cut from a single piece of fabric to the waistline of which two drawer legs each of a single piece are attached without any joining seams, said pieces being so constructed and connected that the combination garment may be opened out flat for 20 ironing so that it may be passed through a mangle in the same manner as a sheet, towel or other piece of flat work, and yet the garment by simply adjusting certain draw strings will comfortably fit the wearer and 25 hang gracefully upon the figure and be supported comfortably without binding on any portion of the body and which presents an attractive appearance.

With this object and others the invention 30 consists in certain novel features of construction as hereinafter shown and described, and specifically pointed out in the claims.

In the accompanying drawing:

35 Figure 1 represents a rear elevation of the garment shown applied.

Fig. 2 is a front elevation thereof, and,

Fig. 3 is an inside view of the garment laid out flat ready for ironing, parts being 40 broken out for convenience in illustration.

In the embodiment illustrated the garment constituting this invention comprises a petticoat 1 and camisole 2 cut from a single piece of fabric or if the fabric be not 45 wide enough from connected strips united at the center of the back by a flat or felled seam 3 as shown clearly in Fig. 3. At the waistline of the camisole and petticoat is arranged a casing 4 extending transversely 50 across the garment and designed to receive a draw string 6 for adjusting the garment to fit the waist of the wearer. The upper edge of the camisole 2 is provided with a similar casing 5 to receive a draw string 7 55 so that the camisole may be adjusted to fit under the arms of the user. This camisole

2 as is ordinary with garments of this character is made of uniform width throughout and as here shown one front edge 8 thereof is straight, while the other is curved as 60 shown at 9, the lower edge thereof merging into a flap 10 carried by one front edge of the petticoat 1, the draw string casing 4 being also secured to this flap as is shown 65 shown clearly in Figs. 2 and 3.

This camisole 2 is provided with the usual shoulder straps 11 which may be of any suitable material, either tape or ribbon and connected to the front and rear of the camisole for supporting the garment over the 70 shoulders of the wearer.

The petticoat 1 may be of any desired 75 length and is hemmed or bound around the bottom and side edges thereof as shown at 12, the flap carrying front edge 13 being designed to overlap the other edge as is shown clearly in Fig. 2.

Two drawer legs 14 and 15 each of a single piece and cut of any desired shape to fit the wearer have their upper edges laid 80 flat on the inner face of the garment at the waistline thereof and secured under the casing 4 by stitching shown at 16, said line of stitching operating also to secure one edge of the casing 4. These drawer legs lap at 85 their rear upper ends as is shown clearly in Fig. 3 and the side edges thereof are provided with separable fastening elements here shown in the form of buttons 17 and cooperating button-holes 18 so that the legs may 90 be opened out flat as shown in Fig. 3 for ironing.

In the use of this garment the arms of the wearer are passed through the straps 11 with the open portion in front and the draw 95 string 6 extended through a slit 19 formed in alignment with the straight edge 13 of the petticoat and the string 6 is passed around to the rear of the wearer and drawn to fit the waist thereof and tied in a bow as shown in 100 Fig. 1, it being understood that the button-holes and buttons 17 and 18 have been first connected to form the completed drawer legs or they may be connected after the garment is placed on the wearer. The draw string 7 105 is then tightened to the desired extent and tied as shown in Fig. 2 and the garment will present the appearance shown in Figs. 1 and 2.

This three-in-one garment is simplicity 110 itself and owing to its formation as above described may be laid out flat as shown in

Fig. 3 for ironing adapting it even to be passed through a mangle for ironing. It of course may be ornamented in any suitable or desired manner to suit the taste of the user.

5 By employing draw strings 6 and 7 at the waistline and the top of the camisole as shown the garment may be adjusted to fit wearers of different sizes or to vary the fullness and the tight fitting of the garment to 10 any user.

The preferred embodiment of the invention is disclosed in the drawings and set forth in the specification, but it will be 15 understood that any modifications within the scope of the claimed invention may be made in the construction without departing from the principle of the invention or sacrificing any of its advantages.

20 What is claimed is:

1. A three-in-one garment comprising a skirt and body cut from a single piece of fabric with one side edge straight and the other provided with a laterally extending 25 flap at the junction of said body and skirt, a draw string defining the waistline at the junction of the body and skirt, and a pair of drawer legs having their upper edges laid flat transversely of the garment at and 30 secured to said waistline with the longitudinal meeting edges of each of said legs separably connected.

2. A three-in-one garment comprising a one-piece skirt and body cut from a single piece of fabric with one side edge straight 35 and the other provided with a laterally extending flap at the junction of said body and skirt, a draw string defining the waistline at the junction of the body and skirt portion and extending transversely through the 40 front wall of said flap, and a pair of drawer legs each formed of a single piece and having their upper edges laid flat transversely across the garment at the waistline thereof and secured thereto and having their 45 rear edges lapping, the longitudinal meeting edges of each of said legs being separably connected to provide for the flat spreading out of the garment for ironing.

3. A three-in-one garment comprising a 50 camisole and petticoat cut from a single piece of fabric with two drawer legs each having detachably connected side edges, and having their upper edges laid flat against the inner face of said first mentioned garment adjacent the waistline thereof and stitched thereto, whereby the garment may be laid out flat for ironing, and a draw string arranged at said connection of the 55 drawer legs with the main garment to adapt 60 it to be quickly adjusted to fit the wearer.

In testimony whereof, I affix my signature hereto.

DOROTHY McHOLLAND.
